UNITED STATES PATENT OFFICE

2,422,395

DOMESTIC APPLIANCE

Kendall Clark, Oakwood, Ohio, assignor to General Motors Corporation, Dayton, Ohio, a corporation of Delaware

Original application March 31, 1942, Serial No. 437,076. Divided and this application November 24, 1943, Serial No. 511,515

16 Claims. (Cl. 192—02)

1

This invention relates to domestic appliance, and more particularly to driving mechanisms for washing machines or the like.

This application is a division of my copending application Serial No. 437,076, filed March 31, 1942, for Domestic appliance, and is a continuation in part of my copending application Serial No. 358,871, filed Sept. 28, 1940, for Domestic appliance.

An object of this invention is to provide a washing machine with a driving mechanism capable of imparting rotation to the tub which contains the clothes and liquid, and reciprocation to the agitator.

Another object of this invention is to provide a driving mechanism for imparting rotary motion to a rotatable driven member, and reciprocating motion to a reciprocable driven member from a unidirectional rotating driving member.

Another object of this invention is to provide a driving mechanism in which a spiral spring clutch is contracted and expanded to make a driving connection and to apply a braking action.

Further objects and advantages of the present invention will be apparent from the following description, reference being had to the accompanying drawings, wherein a preferred form of the present invention is clearly shown.

In the drawings:

Fig. 1 is a vertical cross-section of the driving mechanism;

Fig. 2 is a vertical cross-section of the tub and agitator to be driven by the mechanism of Fig. 1;

Fig. 3 is an enlarged view in perspective of the central portion of Fig. 1; and

Fig. 4 is a fragmentary view of Fig. 1, showing the reciprocating shaft in its upper position.

The washing machine may include a rotatable tub 10, vertically reciprocable agitator 11 and driving mechanism therefor contained in housing 12. The tub 10 may include an inner perforated basket 13 and an outer imperforate cup 14, the construction being such that clothes and liquid may be placed within the tub 10, and the agitator 11 vertically reciprocated while the tub remains stationary. This produces a washing action, after which the tub 10 may be rotated at sufficient speed to cause the liquid to be discharged over the rim 16. During this rotation, the tub 10 is counterbalanced by a weighted ring 16 supported on a resilient rubber collar 17 carried by the extension 18 secured on the tub 10. Details of the operation and construction of the foregoing parts are more fully described and

2

claimed in my copending application Serial No. 358,871, filed Sept. 28, 1940, for Domestic appliance.

The driving mechanism is more fully disclosed in Figs. 1, 3 and 4, in which a unidirectional motor 20 cooperates with the transmission mechanism to rotate the rotatable sleeve 21 and to vertically reciprocate the shaft 22, which are connected respectively with the tub 10 and agitator 11. The motor rotor 23 is carried by a unidirectional rotating drive shaft 24 which has a bearing connection 24a with the rotatable cage 25 at the upper end. The shaft 24 is supported on bearings 26, carried by the stationary portions of housing 12.

The rotatable cage 25 has secured thereto combined brake and driven clutch discs 27, which cooperate with a combined brake and driving clutch disc 28. The arrangement is such that when the driving clutch disc 28 is rotated, the driven clutch discs 27 rotatably drive the cage 25 through the medium of pins 29 on which they are axially movable, but rotationally keyed.

The combined brake and driving clutch disc 28 is connected to the upper end of a spiral spring clutch 30 in such a manner that the disc 28 is maintained stationary when the lever 31 is moved into engagement with the lower end of the spring 30, and in such a manner that the disc 28 is rotatably driven by the shaft 24 when the lever 31 is moved away from the lower end of the spring 30.

The spring 30 holds the disc 28 stationary by expanding against the outer stationary cylindrical wall or sleeve 32. This expansion is caused by the fact that collar 33, which carries the disc 28 and is supported by the upper end of sleeve 32, is rigidly secured to the upper end 34 of the spring 30. When the cage 25 is rotating, and the lever 31 is brought into engagement with the lower end of the spring 30, the lower end of the spring 30 is prevented from rotating while the upper end is rotated in an unwinding direction. The resulting action causes the spring 30 to expand against the outer cylindrical wall 32, which stops rotation of the disc 28. Thereafter there is a sliding brake engagement between the discs 27 and 28 which gradually stops the rotation of cage 25. The brake linings 35 may be secured either to the disc 27 or to the disc 28 or may be loosely held between the discs.

The discs 27 and 28 are held together by a plurality of pins 37, having their heads under the lower disc 27. The pins pass through the discs 27 and their upper parts are surrounded

by compression springs 38, held in place by the washer and cotter-pin construction 39.

The disc 28 imparts rotation to the cage 25 when the motor 20 is energized, and when the lever 31 is moved away from the spring 30. Under these conditions, the spring 30 acts as a one-way clutch, and wraps around the surface 40, which is keyed to the shaft 24, and thus the rotation of the shaft 24 is imparted to the disc 28 through the medium of spring 30 and collar 33. Under these conditions the motor 20 drivingly rotates the sleeve 21 and tub 10.

The motor 20 reciprocates the shaft 22 and agitator 11 when the motor is energized, and when the lever 21 is brought into engagement with the lower end of the spring 30. Under these conditions the spring 30 tends to expand against the outer stationary surface 32 and thus maintains stationary the discs 27 and 28 and the cage 25. Under these conditions, the gear wheel 45, which is keyed to the shaft 24, drives the gear 46 and shaft 47 to rotate the head 48 at the upper end of shaft 47. An obliquely disposed pin 49 cooperates with the sleeve 50 to rock the extension 51 about a vertical arc. The extension 51 cooperates with the ball or cylinder 52 which has a bearing in the head 53 of the lower end of shaft 22. This construction causes vertical reciprocation of the shaft 22 when the motor 20 is energized with the lever 31 in contact with the lower end of spring 30.

The lever 31 is fulcrumed at 60 and is urged in a clockwise direction by the spring 61. A solenoid 62 cooperates with the end 63 of the lever 31, so that when the solenoid is energized, the lever 63 is moved in a counterclockwise direction. The construction is such that, when the solenoid 62 is deenergized, the lever 31 is in engagement with the lower end of spring 30 and thus either applies a stopping force to the rotation of the basket, when the motor is also deenergized, or imparts a vertical reciprocation to the shaft 22 when the motor 20 is energized. When both the solenoid 62 and the motor 20 are energized, the cage 25 and tub 10 are rotated.

In an operation of the device, clothes and liquid are placed in the tub 10, and the motor 20 is energized while the solenoid 62 remains unenergized. Under these conditions the tub 10 is maintained stationary and the agitator 11 is vertically reciprocated because the spring 30 is brought into engagement with the stationary surface 32, thus maintaining the cage 25 stationary while causing the rotary-reciprocating transmission to operate. After a sufficient length of time, the solenoid 62 is energized along with the motor 20. This causes the lever 31 to be moved away from the spring 30, and allows the spring 30 to wrap tightly around the shaft 24 and to impart rotation to the tub 10 through the medium of discs 27, 28 and cage 25. After a sufficient length of time to extract the liquid from the clothes, both the motor 20 and solenoid 62 are deenergized. This applies a brake action to the tub 10 and brings it to a stop, because the lever 31 is brought into contact with the lower end of spring 30, causing the spring to expand against the stationary surface 32 to stop the disc 28 and thus apply a braking action on the disc 27, cage 25 and tub 10.

Other features listed in the drawings are more fully described in my copending application, to which reference is made, if necessary, for a more detailed description thereof.

Lubrication is produced by the gear pump action between the gears 45 and 46, which forces

lubricant through the passageway 70 to the chamber 41 from whence the lubricant flows through spiral grooves 72 and through passageway 73 in shaft 47 to the passageways 74 in sleeve 50 and from thence through passageway 75 through a plug 76 having a small passageway to the interior of the shaft 22 from whence openings may be provided to the various rotating surfaces in the upper part of the transmission. The passageway 74 is plugged at 77.

The operation of the device may be controlled by a single rotatable switch of the type which may be automatically driven by a timing device, or may be manually rotated, or both. Thus the 15 motor 20 and solenoid 62 may be controlled by a rotatable timer switch or hand switch 68, well known in the art. This switch may have a "stop" position, in which all electrical connections from the lines 64 are opened. In the "fill" position the 20 solenoid valve 65 is opened so that water flows through the pressure reducing valve 66 and out of the nozzle 67 into the tub 10 where the clothes and soap have been placed. If the switch 68 is automatically timed, the energization of solenoid 25 65 is of the correct duration to fill the tub 10 to the proper level. Thereafter the switch 68 is automatically or manually turned to the "agitation" position to energize the motor 20 and de-energize the solenoid valve 65 and stop the filling 30 operation. Since the lever 31 is in contact with the lower end of spring 30, the tub 10 is maintained stationary and the agitator 11 is reciprocated to wash the clothes. Thereafter, the switch 68 may be automatically or manually 35 turned to the spin position to energize the solenoid 62 and motor 20. Under these conditions the lever 31 is moved away from the spring 30 and the tub 10 is rotated to extract the liquid from the clothes. If desired the timing mechanism 40 which drives the switch 68 may repeat the cycle automatically one or more times to fill, agitate and spin the clothes one or more times with rinse waters.

While the form of embodiment of the invention as herein disclosed, constitutes a preferred form, it is to be understood that other forms might be adopted as may come within the scope of the claims which follow.

What is claimed is as follows:

- 50 1. A driving mechanism comprising a rotatable member, a rotary driving shaft, spiral spring clutch means, means to cause said spiral spring clutch means drivingly to connect said rotatable member and driving shaft, and means to cause said spiral spring clutch means to disconnect said rotatable member and driving shaft and to apply a braking action to said rotatable member.
- 55 2. A driving mechanism comprising a rotatable member, a rotary driving shaft, a spiral spring clutch, a stationary part, means to cause said spiral spring clutch to connect said rotatable member and driving shaft, and means to cause said spiral spring clutch to disconnect said rotatable member and driving shaft and to apply a braking action between said rotatable member and stationary part.
- 60 3. A driving mechanism comprising a rotatable driven member, a frictional clutch member drivingly connected to said rotatable driven member, a driving member, a stationary part, and a two-way clutch member fixed to said frictional clutch member and selectively connectible to said driving member and to said stationary part.
- 65 4. A driving mechanism comprising a cylin-

cylindrical stationary sleeve, a rotatable member, a driving member coaxial with said sleeve, a spring clutch within said cylindrical stationary sleeve, means to cause said spring clutch drivingly to connect said driving member and rotatable member, while being disconnected from said stationary member and means to cause said spring clutch to connect said rotatable member and stationary sleeve while being disconnected from said driving member.

5. A driving mechanism comprising a cylindrical stationary sleeve, a rotatable member, a frictional clutch connected to said rotatable member, a spring clutch connected to said frictional clutch and extending into said sleeve, a drive shaft coaxial with said sleeve, means to cause said spring clutch to contract on said drive shaft to rotate said rotatable member, and means to cause said spring clutch to expand against said sleeve member to apply a braking action to said rotatable member.

6. A driving mechanism comprising a rotatable member, a frictional clutch member drivingly connected to said rotatable member, a driving member, a stationary part, a two-way clutch selectively connectible to said driving member and to said stationary part, and a solenoid controller for controlling said two-way clutch to connect said clutch selectively to said driving member or to said stationary part.

7. A driving mechanism comprising a rotatable member rotatable about an axis, a driven frictional surface carried by said member, a driving frictional surface cooperating with said first named surface and rotatable about said axis, a driving member rotatable about said axis, a one-way clutch connecting said driving member and said driving frictional surface, and brake means automatically effective when said rotatable member is rotating and said driving member is disconnected by said one-way clutch.

8. A driving mechanism comprising a rotatable member rotatable about an axis, a driven frictional surface carried by said member, a driving frictional surface cooperating with said first named surface and rotatable about said axis, a driving member rotatable about said axis, a stationary part, and a two-way clutch selectively connectible to said driving member and to said stationary part.

9. A driving mechanism comprising a rotatable member rotatable about an axis, a driven frictional surface carried by said member, a driving frictional surface cooperating with said first named surface and rotatable about said axis, a driving member rotatable about said axis, a cylindrical stationary wall coaxial with said axis, a spiral spring having one end secured to said driving frictional surface and engageably surrounding said driving member, and a stop member movable into engagement with said spring to disengage said spring from said driving member and to expand said spring against said cylindrical stationary wall.

10. A driving mechanism comprising a rotatable member rotatable about an axis, a driven frictional surface carried by said member, a driving frictional surface cooperating with said first named surface and rotatable about said axis, a driving member rotatable about said axis, a cylindrical stationary wall coaxial with said axis, a spiral spring having one end secured to said driving frictional surface and engageably surrounding said driving member, and a solenoid operated stop member movable into engagement

with said spring to disengage said spring from said driving member and to expand said spring against said cylindrical stationary wall.

11. A driving mechanism comprising a cylindrical stationary sleeve, a rotatable member coaxial with said sleeve, a driven frictional clutch member secured to said rotatable member, a driving frictional clutch member cooperating with said driven clutch member, a rotatable driving shaft disposed coaxially within said sleeve, a spiral spring secured to said driving frictional clutch member, and having a free end extending into said sleeve and engageably surrounding said driving shaft, and a movable stop member movable into engagement with said free end of said spiral spring.

12. A driving mechanism comprising a cylindrical stationary sleeve, a rotatable member coaxial with said sleeve, a driven frictional clutch member secured to said rotatable member, a driving frictional clutch member cooperating with said driven clutch member, a rotatable driving shaft disposed coaxially within said sleeve, a spiral spring secured to said driving frictional clutch member and having a free end extending into said sleeve and engageably surrounding said driving shaft, an electric motor connected to said driving shaft, a solenoid operated movable stop member movable into engagement with said free end of said spiral spring, and common switch means controlling the energization and deenergization of said motor and solenoid operated movable stop member.

13. In combination, a driving means provided with an annular surface, a rotatable means rotatable relative to said driving means comprising a wound spring clutch member, a normally stationary restraining means provided with an annular surface, said annular surfaces being located adjacent said wound spring clutch member, said clutch member being inherently sprung into frictional engagement with one of said annular surfaces, and a second normally stationary restraining means for engaging one end of said clutch member to cause it to move into frictional engagement with the other annular surface.

14. In combination, a driving means provided with an annular surface, a rotatable means rotatable relative to said driving means comprising a wound spring clutch member, a normally stationary restraining means provided with an annular surface, said annular surfaces being located adjacent said wound spring clutch member, said clutch member being inherently sprung into frictional engagement with one of said annular surfaces, and a second normally stationary restraining means for engaging one end of said clutch member to cause it to move into frictional engagement with the other annular surface, one of said means being provided with a friction slip arrangement for limiting the sudden load upon the engagement of the clutch member.

15. In combination, a driving means provided with an annular surface, a rotatable means rotatable relative to the driving means comprising a wound spring clutch member coiled around said annular surface with a spring tension, a normally stationary restraining means having an annular surface surrounding a portion of said clutch member, and a second normally stationary restraining means for engaging an end coil of said clutch member to unwrap said clutch member from the annular surface of said driving means and to expand said clutch member into engage-

ment with said annular surface of said first restraining means.

16. In combination, a driving means provided with an annular surface, a rotatable means rotatable relative to the driving means comprising a wound spring clutch member coiled around said annular surface with a spring tension, a normally stationary restraining means having an annular surface surrounding a portion of said clutch member, and a second normally stationary restraining means for engaging an end coil of said clutch member to unwrap said clutch member from the annular surface of said driving means and to expand said clutch member into engagement with said annular surface of said first restraining means, one of said means being provided with a friction slip arrangement for limit-

ing the sudden load upon engagement of the clutch member.
